(57) **CLAIM**

The ornamental design for a flow control valve, as shown and described.

DESCRIPTION

FIG. 1 is a front, top and left side perspective view of a flow control valve showing a first embodiment of our new design; FIG. 2 is a rear, top and right side perspective view thereof; FIG. 3 is a front view thereof; FIG. 4 is a rear view thereof; FIG. 5 is a top plan view thereof; FIG. 6 is a bottom plan view thereof; FIG. 7 is a left side view thereof; FIG. 8 is a right side view thereof; FIG. 9 is a front, top and left side perspective view of a flow control valve showing a second embodiment of our new design; FIG. 10 is a rear, top and right side perspective view of FIG. 9; FIG. 11 is a front view of FIG. 9; FIG. 12 is a rear view of FIG. 9; FIG. 13 is a top plan view of FIG. 9; FIG. 14 is a bottom plan view of FIG. 9; FIG. 15 is a left side view of FIG. 9; FIG. 16 is a right side view of FIG. 9; FIG. 17 is a front, top and left side perspective view of a flow control valve showing a third embodiment of our new design; FIG. 18 is a rear, top and right side perspective view of FIG. 17; FIG. 19 is a front view of FIG. 17; FIG. 20 is a rear view of FIG. 17; FIG. 21 is a top plan view of FIG. 17; FIG. 22 is a bottom plan view of FIG. 17; FIG. 23 is a left side view of FIG. 17; and, FIG. 24 is a right side view of FIG. 17.

The broken lines depict portions of the flow control valve that form no part of the claimed design.
